UNITED STATES PATENT OFFICE.

EMMA A. RUNNER, OF ITHACA, NEW YORK.

GLOVE-FINGER-TURNING DEVICE.

1,104,006.

Specification of Letters Patent. Patented July 21, 1914.

Application filed February 26, 1914. Serial No. 821,157.

To all whom it may concern:

Be it known that I, EMMA A. RUNNER, a resident of Ithaca, in the county of Tompkins and State of New York, have invented 5 certain new and useful Improvements in Glove-Finger-Turning Devices; and I do hereby declare the following to be a full, clear, and exact description of the invention, such as will enable others skilled in the art 10 to which it pertains to make and use the same.

This invention relates to glove turners and particularly to a hand device for turning glove fingers.

15 The object of the invention is to provide a device of the kind named adapted for insertion in a glove finger, to clasp the material of the finger on the inside and at the finger end only, and to be then withdrawn 20 thus turning the finger neatly from tip to bottom without danger of tearing or otherwise injuring the glove.

25 The invention consists in the device hereinafter described and particularly pointed out in the claims.

30 In the drawing which illustrates the invention and forms part of the specification;—Figure 1 is a side elevation of the device in open condition; Fig. 2 is an end view with the jaws open; Fig. 3 is a like view with the jaws closed; Fig. 4 is a vertical central section of a portion of the device at the finger grasping end.

35 The device comprises two members, 1, 2, pivoted together at 3. Member 1 has a handle 4 readily grasped and held by the user, and member 2 is preferably shorter and terminates in a thumb pressure end 5. A spring 6 on the handle side of the pivot 40 normally holds the opposite ends, which are the grasping ends, together. These finger-entering grasping members, 1, 2, are semicylindrical and fit together edge to edge and have nicely rounded tips, which are 45 concave on the inside. The device as described in this paragraph is not herein claimed. Experience has shown that with a device thus made it is difficult to press or work the tip of the glove finger which is 50 being turned between the extreme ends of the grasping members without frequently accidentally causing the material of the finger at a distance back of the end to be caught between the separated edges of the opened members 1, 2, and when the finger is thus 55 caught, say a half inch or more from the

tip, it becomes impossible to turn the finger, and with gloves of delicate material tearing results. The present improvement overcomes these difficulties.

60 For the purpose mentioned I provide obstructions which prevent the glove-finger end being pushed in too far between the tips of the members 1 and 2, and also prevent the finger, or any part of the glove, from entering between the sides of the opened members 1, 2, back of the tip, when the members are open. Numeral 60 denotes a fine wire coil, which preferably tapers a little toward the pivot of the device, though 70 the invention is not limited to said taper. The coil is slipped on when the members 1, 2, are closed, but is loose enough to permit easy opening of the grasping end to the required extent, which for light gloves 75 would not exceed three sixteenths of an inch. When the coil is in place, the outer end is passed through a hole 8 in one of the members, and is bent, coiled, or otherwise enlarged, as indicated at 80. This enlargement tends to keep the wire end in the hole, 80 but other means may be used for said purpose. The main use of the wire inside of the hollow members is to obstruct the interior space of the members near the tip, say, 85 one third of an inch back from the tip, to prevent the user pushing the material of the finger which is being turned in too far, care being taken that the extreme end of the wire be concealed in one of the hollow 90 members where it cannot be caught in the glove. The opposite end of the coil is secured and the end hid adjacent the pivot, being shown connected to the spring, and the end concealed in the hollow between the 95 members 1, 2. The coil when in place, forms a limit to the opening of the members, as well as forming an obstruction to the opening between the edges of the device. The wire being fine and smooth, will not interfere with the easy insertion of the device 100 in glove fingers.

105 The device described will uniformly grasp the finger being turned at the inside of its tip only, and will when withdrawn give a safe, neat and complete turn of the finger.

Without limiting myself to all details described, what I claim as my invention and desire to secure by Letters Patent of the 110 United States is:—

1. A glove finger turning device compris-

ing two members pivoted together and having suitable grasping ends, in combination with an obstructing coil around said members back of the grasping end to prevent the 5 finger or glove being grasped back of the tip of a finger.

2. In a glove turning device comprising semicylindrical grasping members having rounded hollow grasping ends, a wire interior 10 obstruction just back of the grasping

ends, said wire extending to the outside and coiled around said grasping members back of the grasping ends.

In testimony whereof, I have signed this specification in the presence of two sub- 15 scribing witnesses.

EMMA A. RUNNER.
